UNITED STATES PATENT OFFICE

1,992,653

WATER CLOSET

Sven Duner, Wheaton, Ill., assignor to Duner Co., Chicago, Ill., a corporation of Illinois

Application March 23, 1934, Serial No. 717,008

16 Claims. (Cl. 4—8)

This invention relates in general to improvements in water closets and has more particular reference to the type of water closet in use in railway cars and similar locations.

Toilets of this class are usually equipped with a dump pan adapted to be rocked downward in flushing, and with a draft or sealing plate at a point below the dump pan, adapted to prevent up-draft through the toilet or closet. This invention has for a principal object the provision of mechanism for rocking the dump pan, so connected with the draft plate that upon the return of the dump pan to original position, the sealing plate is automatically returned to the original position, while during the rocking movement of the dump pan the sealing plate also is automatically rocked from its original position.

A further object of the invention is the provision of mechanism permitting the adjustment of the sealing plate in more or less distant relation to the lower end of the device, thereby permitting the sealing plate to be normally held in partly open position and preventing the freezing of the plate to the lower end of the device.

A further object of the invention is the provision of mechanism of this character in which the sealing plate is retained in its normal or closed position throughout the entire movement of the dump pan for the discharge of waste therefrom, the sealing plate being moved to open position only during the return of the dump pan to its original position.

Another object of the invention is the provision of mechanism in which this opening movement of the sealing plate occurs towards the end of the return movement of the dump pan to its original position, the sealing plate being kept open for a very short time, so that upon the mechanism again resuming its original position with the dump pan in closed position, the sealing plate also is back in its original position.

A further important object of the invention is the provision of mechanism of this character in which the connection between the dump pan and the sealing plate is effected by links under control of a counterweight, means being provided, however, for preventing excess movement of the mechanism for actuating the dump pan.

Numerous other objects and advantages of the invention will be understood from the following description, which, when taken in connection with the accompanying drawings, discloses a preferred embodiment thereof.

On the drawings,

Figure 1 is a side elevation of a water closet

of this type with the dump pan and sealing plate closed;

Fig. 2 is a fragmentary side elevation showing the sealing plate slightly spaced from the sealing edges to prevent freezing;

Fig. 3 is a side elevation showing the mechanism in the position it assumes at the end of the discharge movement of the dump pan;

Fig. 4 is a fragmentary side elevation, similar to Fig. 3, showing the parts after their partial return to closed position;

Fig. 5 is a side elevation showing the sealing plate wide open while the dump pan has almost returned to closed position;

Fig. 6 is a side elevation showing the dump pan and sealing plate in closed condition;

Fig. 7 is a perspective view of details connected with the dump pan actuating mechanism and sealing plate mechanism; and

Fig. 8 is a transverse sectional view of the lower portion of the apparatus, certain of the elements being shown in elevation.

For the purpose of illustrating the present invention, the drawings illustrate a closet of the character generally provided in railway cars. This closet comprises a bowl 1 supported on a stand 2. A dump pan, indicated by reference character 3, normally closes the lower end of the bowl and is fixedly mounted on a transverse shaft 4 extending through the stand 2 and is supported in bearings (not shown) which may be formed integral with the stand.

An arm 5, fixedly secured to the shaft 4 at one end, is provided with a pin 6 extending into a slot 7 which is provided in the lower portion 35 of a link 8. The opposite end of the shaft 4 is equipped with an arm carrying at its free end a counterweight 9 for normally holding the dump pan 3 in closed position, as shown in dotted lines in Fig. 1.

The upper end of the link 8 is pivotally connected with a lever 10 having a handle 11 at one end and being connected at the other or fulcrum end with a flushing valve 12 of any preferred or desired construction, so that upon raising the lever 10, the movement of the dump pan 3 to open position is initiated while at the same time the flushing valve 12 is set in operation in order to thoroughly flush the interior of the bowl. All of these parts are of the usual and well known construction, and are more particularly shown and described in United States Letters Patent Nos. 1,831,528; 1,845,252; 1,898,656 and 1,898,657.

The shaft 16, journalled in bearings 17 of the stand, carries an arm 20 fixed at one end and an 55

arm 21, loosely mounted thereon, having a bifurcated end, the prongs 22 of which serve for loosely supporting the arm 21 on the shaft 16. An extension 23 of the arm 21 is yieldably connected with the end of the fixed arm 20 by a tension element in the form of spring 24.

A pin 25 projecting laterally from the arm 21 between its ends serves as a pivotal support for a lever 26 which carries a weight 27 equipped 10 at its lower portion with a knob 28 of rubber or other suitable sound and shock absorbing material.

A finger 29 projecting upwardly from the lever 26 supports at its free end an adjusting element 15 or screw 30 extending through a tapped opening of the finger 29 against a lug or abutment 31 which projects laterally from the arm 20. A nut 32 on the screw 30 serves to hold the screw in adjusted position relatively to the finger 29 of 20 lever 26.

The spring 24 has a tendency to move the arm 21 clockwise about the shaft 16, and the lever 26 resting with the weight 27 on the floor or water closet supporting medium restrains this rocking 25 movement. The engagement of the adjusting screw 30 with the lug 31 of the arm 20 prevents anti-clockwise movement of the arm 20. It will be apparent that the position of the arm 20 relatively to the other parts may be altered through 30 the adjustment of this screw 30 to permit the sealing plate 14 to seal against the end of stand 2 as shown in Figs. 1 and 8, or to be spaced from its seat as shown in Fig. 2, in which last named position freezing of the sealing plate to the extension 35 of the stand 2 would be prevented. The sealing plate 14 is fastened rigidly to the shafts 16 and 16' through the bracket member 15 (Fig. 8).

In order to connect the mechanism for actuating 40 the dump pan 3 with the elements actuating the draft plate 14, the segment 19 has pivotally secured at one end a link 33 which is provided adjacent its free end with an elongated slot 34 wherein a pin 35 fixed to the weight 27 is 45 adapted to travel. Any extensive movement of segment 19 about the axis of the shaft 4 will also induce a rocking movement of the lever 26 about its pivot 25 on the arm 21.

Owing to the pin 35 being about midway of the 50 slot 34 when the parts are in position of rest (Fig. 1), the initial movement of segment 19 will take place without influencing the weighted arm 26. At the end of the opening movement of the dump pan, however, the parts assume the position illustrated in Fig. 3 wherein the angular link 55 33 of the segment 19 has caused the weighted lever 26 to swing upward about its pivot 25. During this movement the adjusting element 30 (which may have originally held the draft plate 14 in sealed position (Fig. 1) or in spaced position (Fig. 2) has moved away from the abutment 31 of arm 20. If the draft plate is normally spaced, as shown in Fig. 2, the arm 20 may have performed a rocking movement under the influence of a weight 42 on shaft 16' thereby bringing the plate 14 to sealing position, shown in Fig. 3. The weight 27 on arm 26, however, still holds the other arm 21 against clockwise movement to which it is constrained by the spring 24.

70 Viewing Fig. 3, it will also be noted that the pin 35 on weight 27 would then be free to move to the left in the slot 34, and owing to the lever 26 having moved beyond its dead center position, it would have a tendency to continue this swing- 75 ing movement counterclockwise. This action of

the weighted lever 26, however, is prevented by the provision of an abutment or lug 36 projecting from the arm 21, and against which abutment the lower portion of the lever 26 comes to rest.

Upon release of the hand lever 11 after a dumping movement of the pan 3, the counterweight 9 on shaft 4 induces a return movement of the parts to the normal position.

A catch 37 is loosely pivoted at 38 on the inner face of the weighted lever 26, and this catch 10 freely moves during the described swing of lever 26 over a lug 39 which projects from the arm 21 into the path of said catch. It then rests loosely 15 against the hub portion 40 of lever 26 which is supported on the pivot pin 25.

In the return movement of the parts from the position shown in Fig. 3, the segment 19 will swing in a counterclockwise direction about the shaft 4 and the angular link 33 will, after a certain initial idle movement, push against the weighted 20 lever 26 to swing it in a clockwise direction about its pivot pin 25.

During this return movement, the rim of the segment 19 rides over a roller 43 on the arm 21 to hold this arm down against the action of spring 24, and after a certain part of this return movement has been completed, the catch 37 encounters the projection 39 extending laterally from the arm 21. Further downward movement 25 of the weighted lever 26 is thereby momentarily 30 impeded.

The weight 27, owing to its momentum, has a tendency to continue its travel in a clockwise direction (Fig. 4) so that the catch 37 will be firmly pressed against the face of the abutment 35 39. Since, however, the weighted arm is blocked against movement about its pivot 25, owing to the catch 37 being seated on the abutment 39, it is now the entire assembly of arm 21, lever 26, and catch 37 which will rapidly swing about 40 the shaft 16. This movement of the arm 21 will be transmitted through spring 24 to the arm 20 connected with the sealing plate 14 and the latter, therefore, will be rocked away from normal 45 position to the position of Fig. 5.

The weight 27 influences this movement of the arm 20 with considerable leverage to effect an extensive swinging movement of the arm 20 and plate 14 when the knob 28 of the weight 27 strikes the ground, so that the weight ceases to 50 influence the arm 21. The sealing plate 14 is now in fully open position and the arm 21 swung upward.

The counterweight 42, mounted on shaft 16', 55 will now swing back to normal position (Fig. 5) thereby also inducing the return movement of the arm 20, spring 24 and arm 21 to their original position. During this return movement the shelf 31 on arm 20 again comes into contact with the lower end of the set screw 30, slightly lifting the weighted lever 26 and permitting the arm 21 to return to its original position (Fig. 6).

It is thought that the invention and many of its attendant advantages will be understood from the foregoing description, and it will be apparent 60 that various changes may be made in the form, construction and arrangement of the parts without departing from the spirit and scope of the invention or sacrificing all of its material advantages, the form hereinbefore described being merely a preferred embodiment thereof.

I claim:

1. A water closet, comprising a closet bowl, a dump pan pivoted to swing from an outlet sealing position to a dumping position, a draft mem- 75

- ber pivotally located beneath said dump pan, a dumping mechanism comprising elements connecting said dump pan and said draft member, means for normally constraining the draft member to a predetermined position, and means operable by the dumping mechanism for temporarily swinging said draft member to wide open position and back again to said first mentioned predetermined position.
- 10 2. A water closet, comprising a closet bowl, a dump pan pivoted to swing from an outlet sealing position to a dumping position, a sealing plate pivotally supported below said dump pan, dumping mechanism including elements connecting said dump pan and said sealing plate, means for normally constraining the sealing plate to a predetermined position, means for varying the predetermined position of said sealing plate, and means operable by the dumping mechanism for temporarily swinging the sealing plate to wide open position and back to the predetermined position.
- 15 3. A water closet, comprising a closet bowl, a dump pan pivoted to swing from an outlet sealing position to a dumping position, a sealing plate located beneath said dump pan and pivotally supported relatively thereto, dumping mechanism including elements connecting the dump pan with the sealing plate, and means operable by the dumping mechanism during the return movement of the dump pan to sealing position for temporarily swinging the sealing plate to wide open position and back to its original position.
- 20 35 4. A water closet, comprising a closet bowl, a dump pan pivoted to swing from an outlet sealing position to a dumping position, a sealing plate pivotally supported in the water closet, dumping mechanism including elements connecting the dump pan and the sealing plate, means for normally constraining the sealing plate to a predetermined position, and means operable by the dumping mechanism for temporarily swinging the sealing plate to wide open position and back to the first mentioned predetermined position when the dump pan approaches sealing position.
- 25 5. A water closet, comprising a closet bowl, a dump pan pivoted to swing from a sealing position down to a dumping position, a sealing plate pivotally supported relatively to the bowl, an arm fixedly connected with the sealing plate, a second arm, dumping mechanism, a tension element interposed between said two arms, and means operated by the dumping mechanism for preventing movement of the second arm during the greater part of the movement of the dumping mechanism and for releasing said second arm to a movement transmitted to the first named arm and sealing plate during a part of the operating movement of the dumping mechanism.
- 30 60 6. A water closet, comprising a closet bowl, a dump pan pivoted to swing from an outlet sealing position to a dumping position, a sealing plate pivoted beneath said dump pan, means for normally constraining the sealing plate to a predetermined position, an arm fixedly connected with said sealing plate, a second arm loosely connected to said first named arm, a yielding element interposed between said two arms, dumping mechanism connected with said second arm, and means operated by the said dumping mechanism for preventing movement of said second arm relatively to the first named arm during the greater part of the movement of said dumping mechanism and for releasing said second
- 35 40 45 50 55 60 65 70 75 arm to the action of said yielding means interposed between said arms during another part of the movement of the dumping mechanism.
7. A water closet, comprising a closet bowl, a dump pan pivoted to swing from an outlet sealing position to a dumping position, a sealing plate pivoted to the bowl below said dump pan, dumping mechanism having elements connecting the sealing plate with the dump pan, an arm fixedly connected with the sealing plate, and means on one of the elements controlled by the dumping mechanism for selectively determining the normal position of said sealing plate relatively to the bowl.
8. A water closet, comprising a closet bowl, a dump pan pivoted to swing from an outlet sealing position to a dumping position, a sealing plate pivoted to the bowl beneath the dump pan, dumping mechanism, elements connecting said dumping mechanism with the sealing plate, an arm fixed to the sealing plate, the connecting elements between the dumping mechanism and the sealing plate including a weighted link, and means on said weighted link engaging the arm of the sealing plate for selectively holding said sealing plate in a predetermined position in respect of the bowl.
9. A water closet, comprising a closet bowl, a dump pan pivoted to swing from an outlet position to a dumping position, dumping mechanism, a sealing plate, a shaft on which said sealing plate is pivotally mounted, an arm fixedly connected with said sealing plate, a second arm loose on said shaft, and a pair of links connected with said second arm and with the dumping mechanism respectively and movably connected with each other, and a yielding means interposed between said arms.
10. A water closet, comprising a closet bowl, a dump pan pivoted to swing from an outlet sealing position to a dumping position, a sealing plate located beneath said dump pan, a shaft for pivotally supporting said sealing plate, an arm fixedly connected with the sealing plate, a second arm loose on the pivotal shaft, a spring interposed between said arms, a weighted lever connected with said second arm and constraining the latter to move the sealing plate to opening position, and means in cooperation with said weighted lever for normally limiting the movement of said loose arm to a position in which the sealing plate is maintained in a predetermined relation to the bowl, dumping mechanism, and means for connecting the dumping mechanism with said arm controlling lever.
11. A water closet, comprising a closet bowl, a dump pan pivoted to swing from an outlet sealing position to a dumping position, a sealing plate disposed beneath said dump pan, a shaft pivotally supporting said sealing plate, an arm fixed to said sealing plate, a second arm loose on said shaft, a tension element constraining the two arms to move towards each other, a second element normally preventing movement of said arms towards each other, dumping mechanism, said last named element being connected with the dumping mechanism, and means for rendering said last named element inoperative during a portion of the movement of the dumping mechanism to permit said arms to approach each other and to induce movement of the sealing plate.
12. A water closet, comprising a closet bowl, a dump pan pivoted to swing from an outlet sealing position to a dumping position, a sealing plate located beneath said dump pan, a shaft pivotally

- supporting said sealing plate, an arm fixed to said shaft and sealing plate, a second arm loose on said shaft, a weighted lever movably connected with said second arm and having means determining the position of said first named arm and sealing plate, a spring interposed between said arms, a toilet dumping mechanism, and means for movably connecting said weighted lever with said dumping mechanism.
13. A water closet, comprising a closet bowl, a dump pan pivoted to swing from outlet sealing position to dumping position, a sealing plate beneath said pan, a shaft for pivotally supporting said sealing plate, an arm fixed to said sealing plate, a second arm loose on said shaft, a spring interposed between said arms, a weighted lever pivoted to said second arm and constraining the latter in a direction towards the first named arm, the movement of said second arm towards said first named arm being prevented by engagement of the weighted lever with the water closet supporting medium, a dumping mechanism, means movably connecting said weighted lever with said dumping mechanism, and means on said second arm for limiting the movement of said weighted lever relatively to said second arm upon actuation of the dumping mechanism.
14. A water closet, comprising a bowl, a dump pan pivoted for movement from sealing position to dumping position, a sealing plate beneath said dump pan, a shaft on which said sealing plate is pivotally supported, an arm fixed to said sealing plate, a second arm loose on said shaft, a spring interposed between said arms, a weighted lever

connected with said second arm and controlling the position of said second arm relatively to the first mentioned arm, dumping mechanism, means for swinging said weighted lever relatively to said second mentioned arm upon actuation of the dumping mechanism, and means for preventing return swinging movement of said weighted lever relatively to said second arm upon return movement of said dumping mechanism.

15. A water closet, comprising a closet bowl, a dump pan pivoted for movement from sealing position to dumping position, a sealing plate beneath said dump pan, a shaft pivotally supporting said sealing plate, dumping mechanism, arms on the pivotal shaft for the sealing plate, links connecting the dumping mechanism with one of said arms, and means on one of said arms for limiting the movement of one of said links without limiting the movement of the dumping mechanism.

16. A water closet, comprising a closet bowl, a dump pan pivoted for movement from sealing position to dumping position, a sealing plate beneath said pan, a shaft pivotally supporting said sealing plate, a toilet dumping mechanism, an arm yieldingly connected with the sealing plate, means for locking said arm against movement during a part of the movement of the dumping mechanism, and means operable upon arrival of the dumping mechanism in a predetermined position for releasing said locking means, and means for actuating the sealing plate subsequent to the release of said lock.

SVEN DUNER.
